CLAIM

The ornamental design for a toilet brush, as shown and described.

DESCRIPTION

FIG. 1 is a perspective view of a toilet brush showing our new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a front side perspective view thereof, shown the separated state;

FIG. 9 is a rear side perspective view thereof, shown the separated state;

FIG. 10 is a perspective view thereof, shown the dismantling state;

FIG. 11 is an enlarged detail view of area 11 shown in FIG. 3; and,

FIG. 12 is an enlarged detail view of area 12 shown in FIG. 5.

The dash broken lines shown encircling the enlarged detail views in FIGS. 3, 5, 11 and 12 are for annotative purposes only while all other broken lines are included for the purpose of illustrating portions of the toilet brush; the broken lines form no part of the claimed design.
